UNITED STATES PATENT OFFICE.

JONES A. JOHNSTON, OF ROCHESTER, NEW YORK.

STEAM WASHING-MACHINE.

SPECIFICATION forming part of Letters Patent No. 366,220, dated July 12, 1887.

Application filed February 2, 1885. Serial No. 154,665. (No model.)

To all whom it may concern:

Be it known that I, JONES A. JOHNSTON, of Rochester, New York, have invented certain Improvements in Steam Washing-Machines, 5 of which the following is a specification, reference being had to the accompanying drawings.

My invention relates to certain improvements in steam washing-machines, which improvements are fully described in the following specification and the novel features thereof specified in the annexed claims.

My improvements in washing-machines are illustrated in the accompanying drawings, in which—

15 Figure 1 is a side elevation, partially in section. Fig. 2 is an end view. Fig. 3 is a central transverse section. Fig. 4 is a plan view, the cover of the condensing-chamber being removed. Fig. 5 is a plan view, the condensing-20 chamber being removed.

My improved washing-machine consists, essentially, of a suitable vessel or boiler, A, provided with a perforated false bottom, B, the perforated steam-distributer C, and condensing-chamber D. The boiler A is made of any suitable shape and dimensions for the amount of work to be performed. The false bottom B, which may be made of either perforated sheet metal or of wire-cloth, is supported in 25 the boiler at a short distance above its bottom in any suitable manner. I prefer to make the false bottom removable, and for this purpose it is conveniently supported by the legs F, Fig. 1. Above the false bottom is placed 30 the steam-distributer C, which consists of a tube of any suitable shape or dimensions formed of wire-gauze or perforated sheet metal, and supported in position by the steam-passage E, which is open at the lower end, 35 which rests on the false bottom and communicates freely with the distributer C. The steam-passage may be made either of wire-gauze or perforated sheet metal. One or more steam-passages, E, may be used, if desired. The 40 distributer and passage are preferably connected together, so that they can be removed together from the boiler. As shown in the drawings, the boiler is preferably made smaller toward its bottom, as this construction facilitates 45 shipment in nests. Above this boiler is placed the condensing-chamber D, which consists of a suitable tray or vessel having a re-

movable cover or lid, G, and having its bottom provided with one or more openings, H, through which the steam escapes from the 55 boiler into the chamber, and a number of smaller perforations, I, through which the condensed steam falls back onto the clothes in the boiler. The condensing-chamber is also provided with openings J J on its ends or sides, 60 or both, for the admission of air, which assists in the circulation of the steam.

The operation of my improved washing-machine will be readily understood. The space in the boiler below the perforated false 65 bottom having been partially filled with water, the clothes to be washed are introduced into the boiler above the false bottom and around the steam-distributer. The condensing-chamber is arranged in place above the boiler and 70 heat applied in any convenient way to the lower part of the boiler. The steam rising from the water passes through the steam-passage E and is discharged by the distributer through the mass of clothes in the boiler, 75 thereby thoroughly steaming and cleansing the same and causing a constant movement among them, so that every part of each piece is subjected to the operation. The steam which escapes from the boiler passes through the opening or openings H, and, being in large part 80 condensed in the condensing-chamber, falls back through the openings I into the clothes in the boiler, which are thereby kept continually moist. The bottom of the condensing- 85 chamber may be inclined in one or both directions, in which case a single perforation, I, or row or series of perforations, will answer the purpose required; but I prefer to provide a series of perforations distributed over the 90 bottom, as represented in the drawings. The condensing-chamber is not essential to the action of the distributer; but I prefer to employ it, as it prevents the drying of the exposed surface of the clothes in the boiler. 95

I have demonstrated the utility of my improvements in washing-machines by practical trials of the most thorough character.

I hereby expressly disclaim the inventions shown and described in United States Letters 100 Patent Nos. 135,708, 112,760, and 159,196.

I claim—

1. The combination, with the receptacle A, having the perforated false bottom B and the

wire gauze steam-distributer C, connected to said false bottom by the perforated passage E and projecting a short distance above it, of the condensing-chamber D, constituting the cover for the receptacle, provided with the perforations I in its bottom, whereby the clothes placed in the receptacle upon the false bottom will be thoroughly steamed by the passage through them of the steam from the distributor, and the latter passing up through and into the chamber D will be condensed and the water allowed to drip back upon the clothes, substantially as described.

2. The combination, with the receptacle A, having the perforated false bottom B and the wire-gauze steam-distributer C, connected to

said false bottom by the perforated passage E, of the condensing-chamber D, constituting the cover for the receptacle, provided with the perforations I in its bottom and the perforations J in its ends, whereby the clothes placed in the receptacle upon the bottom and distributor will be steamed by the passage of the steam up through them, and the latter will be condensed in the chamber D and the water allowed to drip back upon them, substantially as described. 20 25

JONES A. JOHNSTON.
